GRAIN SIZE COMPARATOR FOR METALLURGICAL MICROSCOPES

Daniel J. Pikosky, Hamden, Conn., assignor to General Scientific Equipment Co., Inc., Hamden, Conn., a corporation of Connecticut

Filed Sept. 15, 1967, Ser. No. 8,597

Term of patent 14 years

(Cl. D57—1)

FIG. 1

FIG. 2

FIG. 3

FIG. 4

FIG. 5

FIG. 6

FIG. 1 is a perspective view of a grain size comparator for metallurgical microscopes showing my novel design and looking from the left front side thereof;

FIG. 2 is a front end view thereof;

FIG. 3 is a side view thereof;

FIG. 4 is a rear end view thereof;

FIG. 5 is a top plan view thereof; and

FIG. 6 is a bottom plan view thereof.

The broken line indicia has been omitted from FIG. 1 for ease of illustration.

The dominant features of my design reside in the portions shown in full lines.

I claim:

The ornamental design for a grain size comparator for metallurgical microscopes, substantially as shown and described.
